United States Patent Office

Des. 180,839
Patented Aug. 20, 1957

180,839

CHISEL

Leslie F. Mohns, Rockford, Ill.

Application May 17, 1956, Serial No. 41,532

Term of patent 14 years

(Cl. D93—4)

Fig. 1.

Fig. 2.

Fig. 1 is an elevational view of a chisel embodying my new design.

Fig. 2 is an elevational view taken from the right of Fig. 1.

The dominant features of my design reside in those portions shown in full lines.

I claim:

The ornamental design for a chisel, as shown and described.
